UNITED STATES PATENT OFFICE.

ELMER B. THOMPSON, OF DES MOINES, IOWA, ASSIGNOR TO AUTOMOTIVE RADIATOR MACHINE COMPANY, OF FORT DODGE, IOWA, A CORPORATION.

DESIGN FOR AN AUTOMOBILE-RADIATOR-REPAIRING-MACHINE FRAME.

57,794.

Specification for Design.

Patented May 3, 1921.

Application filed September 7, 1920. Serial No. 408,793. Term of patent 14 years.

To all whom it may concern:

Be it known that I, ELMER B. THOMPSON, a citizen of the United States, and a resident of Des Moines, in the county of Polk and State of Iowa, have invented a certain new, original, and ornamental Design for an Automobile - Radiator - Repairing - Machine Frame, of which the following is a specification, reference being had to the accompanying drawing, forming part thereof.

The figure is a perspective view of a radiator repairing machine frame showing my new design.

I claim:

The ornamental design for an automobile radiator repairing machine frame, as shown.
Des Moines, Iowa, June 3, 1920.

ELMER B. THOMPSON.
